UNITED STATES PATENT OFFICE

FRANCIS L. MURPHY, OF HARRISON, NEW YORK

PERPETUAL CALENDAR

Application filed August 28, 1930. Serial No. 478,389.

This invention relates to calendars of the type known as perpetual, and more particularly to mechanical calendars of this character having relatively movable parts. One of the objects thereof is to provide a simple, inexpensive and easily operable calendar of the above character. Another object is to provide an accurate calendar of the nature described, in the use of which no additional manipulation or calculation is necessary to accommodate it for correct leap year determinations. Other objects will be in part obvious and in part pointed out hereinafter.

The invention accordingly consists in the features of construction, combination of elements, and arrangements of parts as will be exemplified in the structure to be herein-after described and the scope of the application of which will be indicated in the following claims.

In the accompanying drawings in which is shown one of the various possible embodiments of my invention,

Figure 1 is a front view of the device; Figure 2 is a similar view of a disk normally mounted rotatably behind the face of the device as seen in Fig. 1; and

Figure 3 is a cross section taken on line 3-3 of Fig. 1.

So-called perpetual calendars, such as have been heretofore known, have usually been designed to cover relatively short periods of time varying from fifty to two hundred years. Such calendars have not provided for leap year determinations without additional movement of parts of the device, or without reference to tables with the aid of which leap year determinations might be calculated. The present invention provides a truly perpetual calendar composed of two principal parts, one movable relatively to the other, with the month, day and year information so distributed and arranged as to make possible, with a single setting of the calendar, a direct determination of the day of the week upon which any particular date falls while, at the same time, showing the calendar for the whole of that year. The device also provides that when a setting is made for a particular year the calendar dis-

played will be appropriate, not only for that year but, for every one of the century-years shown in connection with that year; and by furnishing additional slots in one of the members of the device, the calendar can be made truly perpetual for a full period of four hundred years or longer, if desired. Thus with the present device any determination within the four hundred year period for which the calendar is designed may be found by moving a single part of the device relatively to the other part.

Referring to Fig. 1 of the drawings, the present embodiment of my invention will be seen to comprise a top sheet or plate A which may be made out of paper, cardboard, celluloid, or any suitable material, a back plate B, and an intermediate rotatable disk C. The latter is pivotally mounted at its center, as at 10, so as to be rotatable between the front and back sheets A and B; and the front and back sheets are so formed or proportioned relatively to the center point 10 that an edge of the disk projects beyond the side of the sheets, as at 11, providing easy means for manipulating the device. The operator may turn the disk by simply moving his finger up or down along the projecting edge thereof.

The front sheet is provided with certain calendar data as will now be described. In the upper part of the sheet A is a vertical opening 12 and arranged upon either side of this opening are seven calendar month formations arranged systematically with respect thereto. These month formations include all of the variations occurring throughout the year; as they represent the seven arrangements determined by the day of the week upon which the first day of the month falls and provide for the twelve calendar months of the year. At 13 is placed the month beginning on Sunday; directly opposite, at 14, is the month beginning on Monday and so on through the days of the week, each month formation being placed alternately on opposite sides of the slot 12 in a generally staggered arrangement. From each monthly formation a lead line and bracket, as at 15, 16, indicates a certain horizontal section of the

vertical slot 12 as appertaining to the particular month formation to which the lead line is attached. The slot 12 is arranged radially with respect to the center 10. Also arranged 5 radially about that center and beneath the calendar formations are four substantially segmental slots having a century indication adjacent the outer edge of each. Thus 17 shows that one slot is to be used for 18th 10 century determinations. The 19th century determinations will fall within slot 18; the 20th century determinations within the slot 19, and the 21st century determinations within the slot 20. Arranged radially along the 15 edge of each of the slots the century number is repeated several times so that century year numbers which are provided upon the disk C, as will be more fully described, may be read in connection with these repeated century 20 numbers in order that a particular year of the century may be located by the operator.

Referring to Fig. 2, the design of the disk C and the data thereon will now be described. On this disk a century-year table is arranged 25 in definite relation to a plurality of different groupings of the year-month names or symbols. As is well known, the first and last days of each year, excepting leap years, fall upon the same day of the week, from which it follows that the first of January of any year, excepting leap year, falls upon a day one day later in the week than the first of January in the year immediately preceding it. For example, the first day of January 1903 falling 30 on Thursday, the first day of January, 1904, will fall on Friday, etc. As there are only seven days in the week there are only seven different calendar formations for the twelve months of the year. By making all of the 35 calendar formations of thirty-one days length, therefore, the seven formations will provide calendars for the twelve months of the year. Therefore, if the seven different calendar formations are arranged in a systematic order showing the first formation with the first day falling on Sunday and the 40 seventh formation with the first day falling on Saturday, there will be provided a calendar for an entire year, each calendar formation providing for one or more months of 45 that year.

Now every fourth year, excepting the years 1700, 1800 and 1900, of the four centuries comprehended in my device, is a leap year 50 and has one day more than ordinary years. If it were not for these leap years, the calendar formation would be the same, in any century, every seven years; but a leap year occurring every four years, a calendar formation 55 repeats itself in any century every twenty-eight years. Further, starting from any given year and placing the seven calendar formations with the correct month names appropriately arranged with respect to them, 60 it will be found that the calendar progresses

in regular order from that year to the following year until a leap year. Because February has twenty-nine days, the calendar formation for March of the leap year to February of the succeeding year will be found one day later, 70 or one calendar formation further on. For example, in 1909 the first of March falling on Monday would appear in the second calendar formation; in 1910 the first of March, on Tuesday, in the third calendar formation; in 1911, on Wednesday, in the fourth calendar formation; but in 1912, a leap year with February having twenty-nine days, the first of March will be on Friday, two days later 75 instead of one, and in the sixth calendar formation instead of the fourth.

Now, if the years for a given period of time, which may be for the whole century or a part thereof, are placed in chronological order and tabulated in columns or groups of twenty-eight for each century, and the seven calendar formations showing the first of the month falling on Sunday and progressing until the first of the month in the seventh formation shows it falling on Saturday, are 80 arranged in an appropriate manner with respect to the century tabulation of years, then by starting at any year and placing the month names of that year in proper relation to the correct calendar formation for that year and proceeding as outlined above, the month names for any prior or subsequent year may be inserted in correct relation to that year so as to indicate the proper calendar formation.

The years ending in 00 are leap years only when the whole year (as in 2000) is divisible by 400. Therefore, the years 1700, 1800 and 1900 not being leap years, it is necessary to have separate columns for the years in these 90 centuries. But inasmuch as these century leap years occur every four hundred years, the calendar as shown for 1600 will be the same in every respect as for the year 2000, or in other words, the calendar as worked out 95 for the four hundred years from January 1, 1700, to December 31, 2099, may be used for any other year four hundred years removed from any year shown upon the calendar. The disk C has been designed with the above principles in mind, but it should be understood 100 that while I have found the particular arrangement shown a convenient preferred form of mechanical calendar, this arrangement may be varied without departing from 105 the principle or scope of my invention.

Referring to Figure 2, it will be seen that the disk is divided into twenty-eight substantially segmental parts. Beginning near the periphery of the disk and extending inwardly therefrom, there are provided seven concentric spaces, each space in each segmental part having printed therein the name 110 of the symbol or symbols of one or more months of the year. Each segmental part has 115

a different predetermined arrangement of these months and the whole twenty-eight segments with the months shown therein provide for twenty-eight variations of the calendar during a century. Between the year-month tabulation and the center of the disk is a century-year tabulation and in its formation this table also employs twenty-eight segmental groups and four concentric annular 10 divisions of those groups. The hundred years of the century are arranged in a spiral beginning with the year 00 or 01 at the outer end of the spiral and terminating with the year 99 or 00, as the case may be, at the inner 15 end of the spiral, so that all of the years of the century will fall in twenty-eight groups of four years to a group. With this arrangement all of the years shown in any particular segmental group will be found to 20 have the same yearly calendar formation in any particular century.

Turning to Fig. 1, the operation of the device will now be explained. Should it be desired to find on what day of the week in a 25 particular year, for example, July 1, 1800, falls, the operator by placing his finger upon the edge of the disk where it extends beyond the edge of the device, and turning same so that first one year grouping and then another year grouping appears in the slot belonging to the 19th century, going progressively from lower to higher numbers, or from higher to lower numbers, moves the disk until 00 appears opposite one of the 18's distributed along the edge of the slot. The year-month grouping then appearing in the opening 12 will be correct for 1800, and the calendar for any month will be connected with its name. As July appears opposite the calendar formation which begins on Tuesday, it is seen at once that July 1, 1800, falls on a Tuesday, and every other day of the year 1800 is immediately determinable by referring to the proper calendar formation indicated for 30 the month containing it. It will be noted that with this setting the device shows not only a complete yearly calendar for the year 1800, but as well for the years 1817, 1845 and 1873; and in the slot for the 18th century the years 35 1721, 1749 and 1777; for the 20th century the years 1913, 1941, 1969, and 1997; and in the slot for the 21st century the years 2025, 2053 and 2081. As all of these years have exactly 40 the same calendar, the setting provides a complete calendar for all of them.

By arranging the century years in twenty-eight groups, leap years are taken care of and no different mode of operation is needed 45 for determining a date in a leap year than for determining a date in any common year. Should it be desired to find a date falling in, say, 2110 it will be found by finding the proper calendar for the year 1710, and similarly 50 for any year spaced a four hundred year

period from the years comprehended in this device.

From the foregoing it will be seen that the present invention attains all of the ends and objects hereinbefore set forth in a simple, practical and accurate manner, and that a calendar is provided having many obvious advantages and which may be easily operated without reference to calculation tables or other extraneous data.

As many possible embodiments may be made of the above invention without departing from the scope thereof, it is to be understood that all matter herein set forth or shown in the accompanying drawings is to be interpreted as illustrative and not in a limiting sense.

I claim as my invention:

1. In a calendar of the nature described, in combination, a member having seven monthly calendar formations suitably arranged thereon, each calendar beginning on a different day of the week; a second member mounted for relative movement with respect to said first member and having thereon the numerals of all the years of a century arranged in twenty-eight groups with the successive numerals of each group forming an arithmetical progression, said second member also having thereon the twelve month-symbols of the year arranged in varying combinations in twenty-eight groups of twelve months each, the century-year groups and the month-symbol groups occupying predetermined relative positions upon said member; indication means on said first member for positioning said second member so that any one of said century-year groups and every year of that group will be visible and occupy a predetermined position relatively to said first member, and simultaneously the appropriate twelve-month group for all of the years shown will appear in appropriate relation to the said seven calendar formations.

2. In a calendar of the nature described, in combination, a member having seven monthly calendar formations suitably arranged thereon, each calendar beginning on a different day of the week; a second member mounted for relative movement with respect to said first member and having thereon the numerals of successive years for a desired period of time arranged in a plurality of groups with the successive numerals of each group following an arithmetical progression, said second member also having thereon the twelve month-symbols of the year arranged in varying combinations in a plurality of groups of twelve months each, the year-numeral groups and the month-symbol groups occupying predetermined relative positions on said member; indication means on said first member for positioning said second member so that any one of said numeral-year

groups and every year of that group will be visible and occupy a predetermined position relative to said first member, and simultaneously the appropriate twelve-month group for all of the years shown will appear in appropriate relation to the seven calendar formations.

3. In a calendar of the nature described, in combination, a member having seven monthly calendar formations suitably arranged thereon, each beginning on a different day of the week; a disk mounted for rotative movement with respect to said member and having thereon month-symbols arranged radially in a plurality of year-month groups of twelve months each, with the numerals of the century-years whose calendars correspond arranged also in radial groups in predetermined relation to said year-month groups; indication-means on said member for positioning said disk so that any century-year group and every year of that group will be visible and occupy a predetermined position relatively to said member and simultaneously the appropriate year-month group for all the years shown will appear in appropriate relation to the said seven calendar formations; and means for rotating said disk.

4. In a calendar of the nature described, in combination, a member having the century-year numerals arranged successively in tabular form so as to fall into twenty-eight groups, and having the symbols of the twelve months of the year arranged in different combinations in twenty-eight month groups, each year group occupying a predetermined position on said member relatively to all of said twelve month groups; a second member secured to and relatively movable with respect to said first member and having seven monthly calendars each beginning on a different day of the week, suitably positioned thereon; means whereby a year-month group on said first member may appear in visible relationship to said seven calendar formations; and means occupying a predetermined position relatively to said first means whereby a century-year group on said first member may appear in visible relationship to certain century indicia on said second member.

5. In a calendar of the nature described, in combination, a sheet showing thereon seven different calendar formations arranged about an opening through which the symbols of the twelve calendar months may be made to appear simultaneously in appropriate relation to said calendar formations; means comprising four other openings in said sheet, each marked to indicate one of four successive centuries; a second sheet movably mounted beneath said first sheet and having tabulated thereon a plurality of groups of year-month symbols, each group presenting a different arrangement of the twelve months of a year,

and also year indications covering a century tabulated in a chronological series of years in a plurality of groups corresponding in number and related in position to said groups of year month-symbols, said second member being so mounted and movable with respect to said first member that all of the years of four centuries whose calendars are the same may be read at the same time through said four openings and simultaneously the appropriate month-symbol group may be read through said first opening.

6. In a calendar of the nature described, in combination, a pair of upper and lower relatively movable members; the lower thereof having tabulated thereon the symbols for the twelve months of the year repeated in a plurality of groups in which the twelve months are differently arranged, each group being associated with a selected group containing those certain years of the one hundred years of a century when such monthly grouping is appropriate; said upper member having thereon various calendar formations determined by the day of the week upon which the first of the month falls, and century indications covering four successive centuries; and means whereby one of said month-symbol groups of twelve months and four of said year groups may be seen simultaneously in definite relation to said calendar formations.

7. In a calendar of the nature described, in combination, a front member having a slot and a century number adjacent thereto, said member also having an opening and seven week-month calendar formations each beginning on a different day of the week arranged in a systematic manner adjacent said opening; a movable member behind said front member having twenty-eight columns containing different arrangements of the twelve-month names of the year and also the one hundred years of a century arranged in twenty-eight columns, said columns being so arranged on said movable member that when one of said year columns registers with said slot in said front member an appropriate month-name column of twelve months will register with said opening, the month-symbols then indicating the sequence of calendar formations appropriate for the century-years shown.

8. In a calendar of the nature described, in combination, a front member having four slots and a century number adjacent each thereof, said member also having an opening and seven week-month calendar formations each beginning on a different day of the week arranged in a systematic manner adjacent said opening; a movable member behind said front member having twenty-eight columns of month-names and twenty-eight columns of century-years, said columns being so arranged on said movable member that when

one of said year columns registers with one of said slots in said front member an appropriate month-name column will register with said opening and show the twelve months of 5 the year, the month-symbols then indicating the sequence of calendar formations appropriate for the century-years shown in said one century slot, which sequence will be the same for the years appearing in the other 10 century slots.

9. In a calendar of the nature described, in combination, a plate upon which is tabulated a chronological series of year-numerals in a series of adjacent rows, each row containing 15 twenty-eight successive years, and also providing on said plate twenty-eight columns each containing a predetermined arrangement of the twelve calendar month-names; a second plate relatively movable with respect 20 to said first plate and having calendar formations thereon in systematic arrangement with respect to an opening through which one of said rows of twelve calendar month-names may be seen; and one or more slots in said 25 second plate through which may be seen all of the year numbers during a predetermined period of time for which the arrangement of the month-names shown in relation to the calendar formations is appropriate.

10. In a calendar of the nature described, in combination, a member upon which a plurality of successive year-numbers are arranged in twenty-eight groups, each group forming an arithmetical progression in which 35 the difference between the terms is twenty-eight years, and upon which member twenty-eight month-name groups are arranged in predetermined juxtaposition to said year-groups, each month-name group comprising 40 a different arrangement of the twelve calendar month-names; and means movable with respect to said member to indicate with respect to said month and year groups the day of the week upon which any day of any 45 month of any year within the range of said calendar will fall.

In testimony whereof, I have signed my name to this specification this 25th day of August, 1930.

50 FRANCIS L. MURPHY.
